Assignor to

W. & J. Sloane of New York N.Y.

Letters Patent No. 2133, Dated July 14th 1865

Design for Carpet

The schedule referred to in these Letters Patent, and making part of the same.

To all whom it may concern.

Be it known that I James Hutchinson of Newark in the County of Essex and State of New Jersey, have invented a new and "Improved Design for Carpets" and I do hereby declare that the following is a full, clear and exact description thereof, which will enable others skilled in the art to make and use the same, reference being had to the accompanying drawing forming part of this specification.

In the accompanying photographic view, a piece of carpet embracing my full design is shown, the broken figures thereof being completed by the matching of the carpet, as ordinarily.

My new design consists of an ornamental centre piece made of a square outline, but placed in a diagonal position, with regard to the length of the carpet and equal in its diagonal, to the width of the carpet; surrounding which centre piece and upon each side thereof, are ornamental pieces made of a rectangular shape; and at each corner, diagonally placed ornamental square shaped pieces, the boundaries of each and all of the said pieces being of an ornamented shape and style.

2

The central portion of the main centrepiece a of the carpet is ornamented with a cluster or bouquet of flowers consisting of roses b, rose buds c c e, forget-me-nots d, d, d, and verbenas f, f, f, with which suitable and proper green leaves g, g, g, are intermingled.

The ornamentation of each of the four pieces h, h, h, h, surrounding the sides of the central piece a, are similar, it consisting in intertwining for and through the entire length and in the central portions thereof, wild roses l, l, l, to and with moss foliage m, m, bordered on each side with rose leaves n, n.

The square pieces o, o, at each angle or corner of the central piece a, are each ornamented in their centres with a cluster of white lillies p, p, p, and appropriate leaves p, p.

The borders of each of the ornamented pieces herein above described consists of oak stems r, r, having at their central portions oak leaves s, s, intertwined the same.

I claim as new and desire to secure by Letters Patent.

The design for carpets herein described and represented in the accompanying photograph.

The above specification of my invention signed by me this 17th day of May, 1865.
